[57] **CLAIM**

The ornamental design for a fluid dispensing container with finger grooves as shown and described.

DESCRIPTION

FIG. 1 is a perspective view of a fluid dispensing container with finger grooves constructed in accordance with my new design;

FIG. 2 is a front elevation of the fluid dispensing container with finger grooves, the rear elevation is the same;
FIG. 3 is a side elevation of the fluid dispensing container with finger grooves, the opposite side elevation is the same;
FIG. 4 is a top plan view of the fluid dispensing container with finger grooves; and,

FIG. 5 is a bottom plan view of the fluid dispensing container with finger grooves.

The broken lines in the drawings are for illustrative purposes only and do not form part of the claimed design.
